DEVICE FOR SECURING AND RELEASING LIFEBOATS

Filed Sept. 4, 1920

2 Sheets-Sheet 2

UNITED STATES PATENT OFFICE.

HARRY W. BROADY, OF BAYSIDE, NEW YORK, ASSIGNOR TO AMERICAN BALSA COMPANY, INC., A CORPORATION OF NEW YORK.

DEVICE FOR SECURING AND RELEASING LIFEBOATS.

Application filed September 4, 1920. Serial No. 408,134.

To all whom it may concern:

Be it known that I, HARRY W. BROADY, a citizen of the United States, and a resident of Bayside, borough of Queens, county 5 of Queens, and State of New York, have invented certain new and useful Improvements in Devices for Securing and Releasing Lifeboats, of which the following is a specification.

10 This invention relates to improvements in devices for securing and releasing life-boats, and particularly to that type of device wherein a life-boat is pivotally supported on the deck of a vessel in such a manner as 15 to be tiltable about its longitudinal axis by rocking mechanism which moves the same about its pivotal support.

One of the objects of this invention is to improve and simplify the construction of 20 this type of device so as to enable the same to be manufactured economically.

Another object is to lock or release the actuating lever for tilting the boat supports by means of the gripe-release device or flexible connection for securing the boat to the support, so that the release or fastening of the flexible connection or gripe also releases or fastens the actuating lever, and the fastening device of the flexible connection or 30 gripe preferably comprises the conventional pelican hook, and I am furthermore enabled to utilize the actuating lever for tilting the supports as a portion of the securing means for the boat or boats.

35 Another object of this invention is to produce an extremely simple and effective lever arrangement for tilting the boat support which may not only be secured in its normal non-tilted position by one of the gripe 40 chains but which, when the support is tilted, will cause the support and any boat or boats that may be secured thereon to be automatically locked and retained in tilted position, and the launching of the boat which is released from the support may be facilitated.

Another object of my invention is to produce a lever arrangement for tilting a support which is so disposed or pivoted in relation to the lowering movement of the boat 50 that, when one life-boat of a series which has been nested on said support is being lowered or moved outwardly the weight of such boat will assist in tilting the support and any other boat or boats which may be

mounted upon and secured to said support, 55 and will also assist in causing the actuating lever and its connecting link to be swung into locked relationship with the support in tilted position with or without one or more boats lashed thereto. 60

With these and other objects in view, the invention comprises the combination of members and arrangement of parts so combined as to co-act and cooperate with each other in the performance of the functions 65 and the accomplishment of the results herein contemplated, and comprises in one of its adaptations the species or preferred form illustrated in the accompanying drawings, in which:— 70

Fig. 1 is a side elevation of an embodiment of my invention illustrating the same applied to two life-boats, nested one on top of the other; 75

Fig. 2 is an end view of the nested life-boats shown in Fig. 1 with gripe chains and tilting lever in secured position; and 80

Fig. 3 is an end view showing the gripe chains for the top boat released and the support tilted by the lever mechanism. 85

Referring now to these drawings, 1 designates the deck of a vessel to which is rigidly secured twin supporting cradles or tilting chocks 2 which, as shown, comprise two beams, each of which is pivoted intermediate its ends on a pivot 3 bearing in a bracket 4 secured to the deck of a vessel in any suitable manner. 90

As illustrated the beams 2 are held in their normal horizontal non-tilted position by means of a bell-crank lever 5 which, as shown, is pivoted at 5^a to the deck of the vessel 1 and has its short arm 6 pivotally connected with a link 7 which is, as shown, pivotally connected to the beam 2. When the beam is in normal non-tilted or horizontal position, the short arm 6 of the bell-crank lever 5 will be parallel with and abutting against the deck of the vessel and the link 7 will be substantially vertical and will form a rectangular joint with the said short arm of the bell-crank while the long operating-arm of the bell-crank will be disposed in a vertical position adjacent to the inboard end of the beam. The parts in this position will have sufficient stability to enable the mounting of one or a plurality of boats A on the beams 2 but the lever 5 may, if de- 100

105

sired, be held or may be releasably secured to the end of the beams during mounting.

In the embodiment shown, two boats A are nested and mounted on and secured to twin beams 2 and a lever and link device is used at each end. The lower boat may be releasably secured to the beams 2 as illustrated by flexible connections or gripes 8 each preferably connected at one end to an eye 8^b in the 10 outboard end of the support 2 and having at its inboard end a releasable connection with the inboard end of the support by means of a pelican hook 8^a. Slack may be taken up in the gripes 8 by turn-buckles 9. The upper 15 or top boat is, as shown, secured by the flexible connections or gripes 10 each preferably connected at the outboard end to an eye 10^a in the deck of the vessel and at its inboard end having a pelican hook 11 which is, in the 20 form illustrated, fastened to a ring 12 carried by the lever 5. When thus secured the boats will be securely fastened on the supports 2, and the lever will be held in inoperative on non-tilting position.

25 When it is desired to lower one of the boats, the top boat being connected to the falls 13 of the davits 14, the pelican hook 11 is released and the lever 5 turned down. This will cause an upward push on the link 30 7 and a tilting about the pivots 3 of the supports 2 which will, of course, cause the boats mounted thereon to be likewise tilted.

When in operation, the lever 5 is moved 35 into the position shown in Fig. 3, the supporting beams 2 will, owing to the relative angular positions of the pivots and connection of the link 7 and the short arm 6 of the bell crank lever 5, be locked in tilted position and the launching of the top boat will 40 be greatly facilitated. After connection of the falls to the lower boat, the pelican hook 8^a may be released and this boat lowered with greater ease than if retained in horizontal position.

45 It will be apparent that in the arrangement of levers shown and described, the weight and also the outboard movement by the davits of the boats in launching will assist the operation of turning down of the bell crank lever 5 till it reaches its locking position shown in Fig. 3, and also that one of the boats may be secured on the support and the lever may be fastened in its inoperative or non-tilting position by the simple and conventional pelican hook.

It will be obvious also that in order to 60 procure a rigid and secure locking joint between the bell-crank lever and link and also to obtain an unyielding connection between the lever and flexible connection for securing the boat or boats, it is desirable to arrange the axis of the actuating device or lever in a plane substantially parallel to the plane in which the pivot of the support is disposed.

65 It will also be noted that when my inven-

tion is used in connection with nested boats any motion of the upper boat when secured or in stowed position will create a tension in the flexible connection for gripes 10 which will be transmitted through the bell-crank 70 lever 5 and link 7 to the support 2, and will thus tend to further hold the support and the lower boat in horizontal or non-tilting position, and furthermore that during the swinging out of the upper boat in the event 75 that the lever or levers 5 should not be swung down but on the contrary should be simply released, the upper boat being swung out by the davits will exert such a pressure at the outboard edge of the lower boat as to cause 80 the lower boat and support to tilt enough to permit the upper boat to clear it.

Having described my invention I claim:—

1. In combination, a support for a life boat pivoted on the deck of a vessel and adapted to tilt in an outboard direction, a flexible connection secured at one end outboard of said life boat and adapted to pass transversely across the same, a bell crank lever pivoted adjacent to the inboard side of said support comprising a short arm operatively connected at its free end with the inboard end of said support and a relatively long actuating-arm movable from vertical inoperative position to horizontal support-tilting position and means for releasably connecting the free end of said actuating arm with the inboard end of said flexible connection to fasten the same in said inoperative position.

2. In combination, a support for a life-boat pivoted on the deck of a vessel and adapted to tilt in an outboard direction; a flexible connection for releasably securing a life-boat to said support; a bell-crank lever pivoted on the deck of the vessel and a link having a pivotal connection at one end with said support and a pivotal connection at its opposite end with one arm of said lever, said pivotal connection being arranged to provide a locking joint between the link and lever arm when the parts are in one extreme position and means for connecting the other arm of said bell crank to said flexible connection to releasably secure the same in its other extreme position.

3. The combination with a plurality of nested life-boats, of a suitable support pivoted on the deck of a vessel, a flexible connection for a lower boat secured at one end to the outboard end of said support and having a releasable connection at its opposite end with the inboard end of said support, another flexible connection for the upper boat secured to the deck of the vessel at the outboard end of said support, a bell-crank lever pivoted adjacent to the inboard end of said support on the deck of the vessel, one arm of which has an operative connection with the inboard end of said support and the 120 125 130

other arm has a releasable connection with the inboard side of the flexible connection for the upper boat.

4. The combination with a plurality of 5 nested life-boats, of a suitable support pivoted on the deck of a vessel, a flexible connection for a lower boat secured at one end to the outboard end of said support and having a releasable connection at its opposite end with the inboard end of said support, another flexible connection for the upper boat secured to the deck of the vessel at the outboard end of said support, a lever mechanism pivoted adjacent to the inboard 10 end of said support on the deck of the vessel, one arm of which has an operative connection with the inboard end of said support and another arm has a releasable connection with the inboard side of said flexible 15 connection for the upper boat.

5. The combination with a plurality of nested life-boats, of a suitable support pivoted on the deck of a vessel, a flexible con- 20

nnection for a lower boat secured at one end to the outboard end of said support and 25 having a releasable connection at its opposite end with the inboard end of said support, another flexible connection for the upper boat secured to the deck of the vessel at the outboard end of said support, a bell-crank lever pivoted adjacent to the inboard end of said support on the deck of the vessel, one arm of which has an operative connection with the inboard end of said support and the other arm has a releasable connection 30 with the inboard side of said flexible connection for the upper boat comprising a pelican hook on the said flexible connection and a ring on the lever.

In witness whereof, I have signed my 40 name to the foregoing specification in the presence of two subscribing witnesses.

HARRY W. BROADY.
